UNITED STATES PATENT OFFICE.

JOHN GILSON, SR., OF PORT WASHINGTON, WISCONSIN, ASSIGNOR TO J. E. GILSON COMPANY, OF PORT WASHINGTON, WISCONSIN, A COPARTNERSHIP CONSISTING OF JOHN GILSON, SR., AND JOHN E. GILSON, JR.

DESIGN FOR A WEEDEER.

55,601.

Specification for Design.

Patented July 6, 1920.

Application filed June 17, 1918. Serial No. 240,513. Term of patent 14 years.

To all whom it may concern:

Be it known that I, JOHN GILSON, Sr., a citizen of the United States, residing at Port Washington, in the county of Ozaukee and State of Wisconsin, have invented a new, original, and ornamental Design for Weedeers, of which the following is a specification, reference being had to the accompanying drawing, forming a part thereof.

The figure is a perspective view of a weedeer showing my new design.

I claim:

The ornamental design for a weedeer, as shown.

JOHN GILSON, SR.
